(57) **CLAIM**

The ornamental design for a mobile computer, as shown and described.

DESCRIPTION

FIG. 1 is a front right perspective view of a mobile computer in accordance with the present invention;

FIG. 2 is a front, top, left perspective view of the mobile computer of FIG. 1;

FIG. 3 is a rear, bottom, right perspective view of the mobile computer of FIG. 1;

FIG. 4 is a front elevation view of the mobile computer of FIG. 1;

FIG. 5 is a rear elevation view of the mobile computer of FIG. 1;

FIG. 6 is a right elevation view of the mobile computer of FIG. 1;

FIG. 7 is a left elevation view of the mobile computer of FIG. 1;

FIG. 8 is a top plan view of the mobile computer of FIG. 1; and,

FIG. 9 is a bottom plan view of the mobile computer of FIG. 1.

The broken lines and unshaded regions bounded by broken lines show portions of the mobile computer that form no part of the claimed design.

1 Claim, 7 Drawing Sheets
